PROVISION OF RIP-WIRES IN CANISTERS

Original Filed March 7, 1940

UNITED STATES PATENT OFFICE

2,350,870

PROVISION OF RIP WIRES IN CANISTERS

Peter Bogner, Uxbridge, England, assignor to
 Saml. Hanson & Son Limited, London, England, a British company

Original application March 7, 1940, Serial No.
 322,748. Divided and this application August
 6, 1940, Serial No. 351,619. In Great Britain
 December 22, 1938

6 Claims. (Cl. 220—49)

This application is a divisional of my co-pending United States application Serial No. 322,748, filed 7th March, 1940, for improvement in "The provision of wire-rips in canisters," and now matured into Patent 2,329,328.

This invention is for improvements in or relating to the provision of rip-wires in canisters or the like and is concerned with a canister end-closure having a rip-wire secured in place thereon.

In the present specification and claims the term "canister" is used generically to include all sheet metal containers irrespective of the shape, form or dimensions such containers may have.

One object of the invention is to facilitate retention of the rip-wire in a desired location on the end-closure.

Another object is to provide a canister end-closure with a rip-wire which is held securely in place by being clinched in a ridge or groove formed in the material of the end-closure, so that during the seaming of the end-closure to the body of the canister the wire cannot be displaced from its proper position.

A further object is to provide a can end-closure having a rip-wire located in place in a ridge or groove in the end-closure with the walls of said ridge or groove pressed together to indent the rip-wire into them so as to secure the rip-wire in place and also form a line of weakening in each wall facilitating opening of the finished can by the rip-wire.

Yet another object is to provide a can end-closure which has a rip-wire secured to it and which can be readily seamed to a can-body by a normal seaming process.

A still further object is to provide an improved end-closure which has a rip-wire protruding at one end to the outside of the end-closure, and which can readily have the rip-wire clinched in place without risk of splitting the material of the end-closure in the neighbourhood of the location where the wire projects through the end-closure.

The invention accordingly provides for a canister an end-closure having a central depression to fit within the can-body and a marginal flange for interfolding with the can-body, and having a ridge formed in the material of the closure around the central depression and a rip-wire contained in said ridge and the walls of the ridge clinched together continuously along the whole length of the ridge to grip the rip-wire. The clinching of the walls of the ridge together as aforesaid will serve to hold the rip-wire securely

in position so that the wire cannot become accidentally displaced during the handling of the end-closure or during the seaming operation in which the end-closure is attached to the can-body.

Preferably the walls of the ridge are pressed together sufficiently to cause the rip-wire to be indented into the material of said walls. This will not only serve to hold the wire more firmly in place, but will also form a line of weakening along which, in the finished can, the material of the end-closure may be readily torn when opening the can.

It is preferred in carrying out the invention to provide a shoulder around the centre of the depression as described in United States Patent No. 2,277,066. That is to say it is preferred to have the material of the closure between the central depression and marginal flange continued outwardly from the depression in the form of a shoulder, with the said ridge extending around said shoulder.

The said ridge may be interrupted to form a gap and one end of the rip-wire may protrude through an opening at one end of the ridge at the gap. Alternatively there may be provided a continuous ridge which is reduced in height over a short distance, and one end of the rip-wire may protrude through an opening in the ridge at a junction between the reduced portion and the main portion of the ridge.

During clinching of the walls of the ridge, there is some tendency for the material of the ridge to be split or become porous thereby preventing the formation of a proper seam if the wire passes through an aperture formed in one end of a discontinuous ridge at a location near the general plane of the end-closure. To reduce this tendency the invention further provides a canister end-closure formed with a groove to receive a rip-wire, said groove having an end face apertured for the passage of the rip-wire in such a way that the aperture is raised above the junction between the ridge and those portions of the material of the canister which are positioned laterally of the ridge.

Certain preferred forms of end-closures are illustrated by way of example in the accompanying drawing and will now be described with reference to the drawing in which—

Figure 1 is a detail view in cross-section of a portion of an end-closure as it appears before the rip-wire is applied to it.

Figure 2 is a view corresponding to Figure 1

but showing the rip-wire in place and the walls of the ridge clinched together.

Figure 3 is a view corresponding to Figure 2 showing the walls of the ridge pressed together to indent the rip-wire into the material of said wall.

Figure 4 is a fragmentary view of a portion of an end-closure, seen from the underside, with the rip-wire secured in place.

Figure 5 is a perspective view of a wired end-closure with a portion of the latter broken away to illustrate its cross-section.

Figures 6, 7 and 8 are respectively an end view, a side view and a plan view of the end portion of a wire-receiving ridge or groove.

Figure 9 is a side view in cross-section of the end of the ridge or groove showing a rip-wire passing through it, and

Figure 10 is a side view of a reduced portion of a continuous wire-receiving ridge or groove formed in an end-closure.

Like reference numerals indicate like parts throughout the drawing.

In Figure 1 there is shown a portion of a can end-closure indicated generally at 47 formed as described in United States Patent No. 2,277,066. The end-closure is formed with a central depression 69 and a marginal flange 72, and it will be seen that the material of the end-closure between the depression 69 and flange 72 is continued outwardly from the depression in the form of a shoulder 70, and an upstanding rip-wire receiving ridge or groove 71 extends around the shoulder 70. The side walls of the ridge 71 are shown at 73. The ridge is formed by a fold in the material of the closure. The end-closure 47 is adapted to be seamed to a canister body by interfolding the marginal flange 72 with a seaming flange on the canister body.

In applying the invention to an end-closure of the form shown in Figure 1 a rip-wire 46 is inserted into the ridge or groove 71 and the side walls 73 of the latter are clinched together continuously along the whole length of the ridge to grip the rip-wire, as shown in Figure 2. The clinching of the walls 73 together may be carried out by the use of apparatus as described in my United States Patent application No. 322,748 in which the walls 73 of the ridge 71 are gripped between rotatable rollers 21 and 22 while the end-closure is supported by a holder 28. The side walls 73 of the ridge 71 are urged together around the rip-wire 46. The material of the ridge 71 of the end-closure is thus brought to a re-entrant channel formation or to the form of a substantially closed tube containing the rip-wire 46.

The end-closure in the most preferred form of the invention also has the side walls 73 of the ridge or groove 71 pressed together and in contact on opposite sides of the wire, as indicated in Figure 3 sufficiently to cause the rip-wire 46 to bite or be indented into the material of said walls. Thin places as indicated at 74 are thereby formed in the outside and inside walls 73 of the ridge 71, and the thin portion 74 of the outer wall 73 of the ridge may conveniently form a line of weakening to facilitate opening the completed canister by the use of the rip-wire 46. The pressing together of the side walls 73 of the ridge may be carried out as described in my United States Patent application No. 322,748 by the employment of additional presser or gripper rollers 63 and 64.

Figure 5 shows in perspective the form of the

end-closure as a whole with the side walls 73 of the ridge 71 pressed together along the whole length of the ridge 71. It will be seen that the ridge is interrupted to form a gap 104 and one end of the rip-wire indicated at 76 protrudes through an opening at one end of the ridge at the gap 104, this opening being indicated at 102 in Figures 6 to 9. The projecting end 76 of the rip-wire may be formed to a loop as shown at 82 in Figure 5 and anchored by solder or otherwise at 83 to the central part of the end-closure. The other end of the rip-wire is left inside the end-closure as indicated at 75 in Figure 4 which is an enlarged view of a portion of the end-closure near the gap 104 as seen from underneath the end-closure. The end of the ridge 71 adjacent to the end 75 of the rip-wire may be inclined as indicated at 106, see Figure 5. During the subsequent seaming of the end-closure to a can-body the end 75 of the rip-wire may conveniently be embedded in the seam to assist in ensuring proper operation of the rip-wire when opening the can.

The clinching and pressing together of the walls 73 of the ridge 71 should preferably stop slightly short of the ends of the ridge to avoid splitting the material of the end-closure at these points. In order to assist further in avoiding the tendency for splitting the material of the end-closure, the invention provides an improved formation of the ridge at its ends as shown in Figures 6 to 9. The ridge or groove 47 has an inclined end face 101 adjacent to the gap 104, as shown most clearly in Figures 7 and 9, and the end face 101 is formed with the aperture 102 for the passage of the rip-wire 46. It will be seen that the aperture 102 is raised above the junction between the ridge 47 and those portions of the material of the closure which are positioned laterally of the ridge. This is found to assist the clinching of the side walls 73 of the ridge 71 close to the end of the latter without splitting the material of the end-closure and also to facilitate sealing the opening around the rip-wire. Figure 10 illustrates a modification wherein the ridge 71 instead of being discontinuous is formed with a reduced portion at 105 corresponding to the gap 104. In other words the ridge is continuous and reduced in height over a short distance corresponding to the gap shown in Figure 5. The inclined portions 101 and 106 constitute end faces defined by the reduction in height of the continuous ridge and they correspond to the end walls of the discontinuous ridge. The aperture 102 for the rip-wire is formed in the inclined portion 101, that is to say between the reduced portion and the main portion of the ridge, and is thus raised above the level of the material on either side of the ridge.

In Figure 9 the wire 46 is shown projecting through the opening 102 and the space between the opening and the wire is shown as being filled up with sealing composition at 103 which may be applied externally or internally and may be extended somewhat beyond the opening 102 on the outside or the inside of the end-closure. The sealing composition may be solder or any other suitable material. The space between the rip-wire and the opening 102 in the construction of Figure 10 may be similarly filled up with sealing composition.

In any of the forms of construction shown the interior of the marginal flange 72 of the end-closure may be provided as usual with a gasket of sealing composition such as a latex compound,

and this may be applied to the underside of the marginal flange in known manner and extended inwardly to reach across the clinched side walls 73 of the ridge 71 and fill the shallow recess formed on the inside of the end-closure immediately below the portions of the walls 73 which are in engagement or substantial engagement with one another.

It will be appreciated that the clinching of the walls 73 of the ridge 71 around the rip-wire 46 will serve to hold the latter in place during handling of the end-closure and also during the seaming of the end-closure to a can-body. The frictional grip between the rip-wire 46 and the clinched side walls 73 of the ridge will also usually be sufficient, particularly when the walls 73 are pressed together as shown in Figures 3 and 5, to prevent the rip-wire from sliding along the ridge when a pull is exerted on the projecting end 75 of the wire when opening a completed canister. However as above indicated the end 75 of the rip-wire may be embedded in the seam to assist in avoiding such slippage of the wire along the ridge. Since the lines of weakening are formed by the wire, I eliminate the step of locating the wire properly with respect to said lines as has been necessary in rip-wire closures known heretofore. The wire also reinforces the lines of weakening against accidental rupture in the handling incident to filling, seaming and packing.

To illustrate that the housing of the rip-wire in the ridge in the end-closure is quite independent of the formation of the seam by which the end-closure is secured to the can-body, and also to show how firmly the rip-wire is held in place, it can be stated that the rip-wire could be used for tearing open the central part of the end-closure equally as well before the end-closure is seamed to the can-body as after these parts have been seamed together.

It is to be understood that the invention is not restricted to the precise constructional details shown in the drawing. In some cases the end-closure need have no shoulder such as 70 and the ridge 71 may be formed as a continuation of the material forming the central depression 69.

I claim:

1. A closure for sheet metal containers comprising a sheet metal disc having a marginal flange adapted to be lock-seamed to a container body, said disc also having an upstanding ridge spaced inwardly of said flange, said ridge being provided by a fold in the material of the disc and including side walls, a rip wire disposed between said walls, said walls being in contact with each other on opposite sides of said wire, and said wire biting into the inner surfaces of the walls, thereby forming lines of weakening in said walls and effecting a union of the wire with the closure such as to maintain the assembly thereof during handling and lock-seaming and reinforcing the weakened ridge sufficiently to withstand the stresses incident to such treatment, said ridge being discontinuous and having at least one end sloping downwardly into the general plane of the disc, and an opening in said sloping end

above said plane, one end of said wire protruding through said opening.

2. A closure for sheet metal containers comprising a sheet metal disc having a marginal flange adapted to be lock-seamed to a container body, said disc also having an upstanding ridge spaced inwardly of said flange and including side walls provided by a fold in the material of the disc, and a rip wire disposed between said walls, said walls being compressed onto opposite sides of the wire and said wire biting into the inner surfaces of said walls, thereby forming lines of weakening in said walls and effecting a union of the wire with the closure such as to maintain the assembly thereof during handling and lock-seaming and reinforcing the weakened ridge sufficiently to withstand the stresses incident thereto.

3. A closure as defined by claim 2 characterized by said ridge being discontinuous and having at least one end sloping downwardly into the general plane of the disc, and an opening in said sloping end above said plane, one end of said wire protruding through said opening.

4. A closure as defined by claim 2 characterized by said ridge being continuous and having a portion of reduced depth connected to the remainder by sloping surfaces, and an opening in at least one such surface, one end of said wire protruding through said opening.

5. A closure for sheet metal containers comprising a sheet metal disc having a marginal flange adapted to be lock-seamed to a container body, said disc also having an upstanding ridge spaced inwardly of said flange and including side walls provided by a fold in the material of the disc, and a rip wire disposed between said walls, said walls being compressed onto opposite sides of the wire and into contact with each other on opposite sides of the wire with said wire biting into the inner surfaces of said walls, thereby forming lines of weakening in said walls and effecting a union of the wire with the closure such as to maintain the assembly thereof during handling and lock-seaming and reinforcing the weakened ridge sufficiently to withstand the stresses incident thereto.

6. A closure for sheet metal containers comprising a sheet metal disc having a marginal flange adapted to be lock-seamed to a container body, said disc also having an upstanding ridge spaced inwardly of said flange and including side walls provided by a fold in the material of the disc, and a rip-wire disposed between said walls of the ridge medially of the depth thereof, said ridge being compressed on opposite sides throughout its depth to bring said walls in closer proximity to one another at locations on opposite sides of said wire than at said medial location of said wire and said wire biting into the inner surfaces of said walls, thereby forming lines of weakening in said walls and effecting a union of the wire with the closure such as to maintain the assembly thereof during handling and lock-seaming.

PETER BOGNER.
